Term of patent 14 years

(Cl. D40—1)

FIG. 1.

FIG. 2.

Des. 200,426

PAGE 2

FIG. 3.

FIG. 4.

FIG. 5.

FIG. 1 is a perspective view of a swather embodying our new design and looking at the machine from the left front thereof;

FIG. 2 is a front view thereof;

FIGS. 3 and 4 are left and right side views, respectively, of the machine, and

FIG. 5 is a plan view.

We claim:

The ornamental design for a swather, as shown.
